UNITED STATES PATENT OFFICE.

ARTHUR QUENZER, OF BROOKLYN, NEW YORK.

ARCH-SUPPORTER.

987,599.

Specification of Letters Patent. Patented Mar. 21, 1911.

Application filed July 23, 1908. Serial No. 445,026.

To all whom it may concern:

Be it known that I, ARTHUR QUENZER, a citizen of the United States, residing at 388 Chauncey street, Brooklyn, in the county 5 of Kings and State of New York, have invented certain new and useful Improvements in Arch-Supporters, of which the following is a specification.

My invention relates to a bandage to support the arch of deformed or flat feet caused by insufficient strength of the ligaments to hold the arch in its natural position; and the object of my invention is to provide an easy and flexible bandage-support which will 10 raise the arch gradually by gentle pressure and assist the foot to assume its natural position, and which may be worn inside of the shoe without causing the wearer pain or inconvenience. I attain these objects by means 15 of the supporting device illustrated in the accompanying drawings, in which—

Figure 1 is a side view of my arch supporter shown in position on a foot, the shoe being partly broken away. Fig. 2 is a cross- 20 section through the supporter and foot through the line 2—2 of Fig. 1, to show the manner of securing the supporter on the foot. Fig. 3 is a plan bottom view of my 25 supporter, with the outside casing or cover partly broken away to show the corrugations which I provide in the body portion of the supporter.

The main portion or body of the supporter is preferably made of pliable resilient material, and I have found that rubber is suitable for this purpose. The body is made of such a shape as to conform to the arch of the foot, gradually tapering in thickness 30 from the inside to the outside of the foot, as 35 shown in cross-section in Fig. 2.

It has been proposed to cut notches or slots on the inner side of the supporter in order that it may more easily adjust itself to the conformation of the foot and yield to 40 the movements thereof, but this weakens the supporter so that it does not afford the proper support for the arch, and to a large extent destroys the resiliency by which the arch is gradually raised into its natural position. In my invention I provide a solid 45 homogeneous, resilient body-portion having an unbroken outline so that a firm support is furnished for all parts of the arch, and the thickness can be increased at the highest 50 point of the arch and gradually tapering toward each side. The inner side, which is

next to the foot, has a smooth and unbroken surface so that it may be comfortable to the wearer.

In order that the body of the supporter 55 may properly yield to the movements of the foot, and may conform to the shape thereof, I provide a series of intermediate transverse corrugations *a* upon the outer side thereof which permit the body to yield more readily 60 throughout the central portion thereof and yet permit this portion to be made thicker than the remaining portions. I find that this feature enables my supporter to conform accurately to the shape of the foot and 65 to produce a gentle pressure upon the delicate ligaments of the arch without causing pain or inconvenience to the wearer, and at the same time forming a firm support which 70 assists the foot to assume its natural position. 75

For the purpose of securing the supporter to the foot, I inclose the body *A* in a casing or cover *B* of leather or other flexible material. An elastic strap *C* is fastened at *c* 80 to the outside of the casing, the other end being threaded through a stirrup or loop *D* formed integral with the casing by cutting parallel slots on either side thereof. The strap *C* is threaded through the stirrup *D* 85 from the bottom, the free end *c'* returning upon itself as shown in Fig. 2 so that when the strap is slipped over the foot it will be drawn tightly over the edge of the casing and securely held from slipping, thus avoiding 90 the necessity for buckles or other fastening means, and yet permitting a ready adjustment of the strap when the bandage is off of the foot.

My supporter is intended to be slipped over 95 the stocking and will be securely held in the proper position on the foot as it is being slipped into a shoe.

It will be readily perceived that my arch supporter may be made to fit either the right 100 or left foot, or a foot of any size, as may be desired.

Having now described my invention, what I claim and desire to secure by Letters Patent, is—

1. An arch-supporter for a foot comprising a body of solid homogenous resilient material shaped to conform to the arch of the foot, said body being smooth on the inner side and of greatest thickness through the intermediate longitudinal portion and tapering therefrom toward the opposite

edges, and being provided with transverse corrugations on the outer side of said solid body in the intermediate part of said thickest portion.

5. 2. An arch-supporter for deformed, flat or weak feet comprising a resilient body portion shaped to conform to the arch of a foot, said body portion being smooth on the inner side and provided with corrugations in the 10 outer central portion thereof, a casing inclosing said body portion and having a loop

in the outer side thereof, and a strap attached to the casing and having its free end passing through said loop to be held in fixed position by pressure against the foot of the 1st wearer.

In testimony whereof I affix my signature in presence of two witnesses.

ARTHUR QUENZER.
